UNITED STATES PATENT OFFICE.

HARRY O. RUGH, OF CHICAGO, ILLINOIS, ASSIGNOR TO WESTERN TELEGRAPH COMPANY, OF MINNEAPOLIS, MINNESOTA, A CORPORATION OF SOUTH DAKOTA.

COMPOSITE TELEPHONY AND TELEGRAPHY.

No. 831,525.

Specification of Letters Patent.

Patented Sept. 18, 1906.

Application filed January 13, 1903. Serial No. 138,865

To all whom it may concern:

Be it known that I, HARRY O. RUGH, a citizen of the United States, residing at Chicago, in the county of Cook and State of Illinois, have invented a certain new and useful improvement in Composite Telephony and Telegraphy, of which the following is a full, clear, concise, and exact description, reference being had to the accompanying drawings, forming a part of this specification.

My invention relates primarily to composite telephone and telegraph circuits, though in some of its individual characteristics it is also adapted for use in connection with ordinary telephone systems.

In composite circuits of the character described effort has been made to prevent the telegraphic currents from operating the telephone-receivers that might be simultaneously in use with the telegraphic instruments on the circuit. So far as I am aware this result has not been as effectively accomplished as desired.

In accordance with my invention I provide means associated with the telephone-substation apparatus whereby the telegraphic currents that may find their way to the telephone connections will be diverted from the telephones. To this end I provide a by-path for diverting telegraphic currents from each telephone-receiver, this by-path being of low ohmic resistance and high impedance. The path is made of low ohmic resistance, so that telegraphic currents may readily pass through the same, the impedance in this path not being a material obstruction to such currents; but it is made of high impedance, so that the high-frequency voice-currents will be forced through the receiver. This by-path not only shunts the telephone-receiver, but also desirably shunts the induction-coil or a part thereof, so that the telegraphic currents will neither directly nor indirectly influence the telephone apparatus. It is obvious, however, that the path of impedance may be associated with circuits wherein the association of the receiver with the transmission-line is purely inductive, as is well understood by those skilled in the art.

One feature of the invention may be realized in a telephone system employing telephone-receivers in local secondary circuits, each circuit containing a secondary coil,

while the primaries are adapted for metallic connection with the telephone-line as in common battery practice. Where the invention is in practice with a system of the latter class, the primary coil is shunted by a path of low ohmic resistance containing high impedance, performing the same functions as those hitherto specified. In order that a telephone-station connected with a composite telephone and telegraph line may have signals conveyed thereto without interfering with telegraphic instruments upon the line, a generator of signaling-current is adapted for association with the telephone-line that will produce currents of very high frequency, to which the telegraph instruments will not respond, but to which a signal-receiver properly constructed and arranged will respond at a telephone-station. The transmitting-generator preferably comprises an induction-coil whose secondary is adapted for connection with the transmission-line and whose primary is adapted for inclusion with a local circuit with the battery, the primary coil also desirably constituting the winding of a magnet, this primary winding being included in circuit with the armature and back contact of the armature in the manner of the magnets of ordinary make-and-break or single-stroke bells.

In order that the user of a telephone may signal while he has his receiver applied to his ear without being annoyed by the outgoing signaling-current, I provide a key which as it closes the local circuit opens the circuit containing the subscriber's telephone instrument. The signal-receiver that I prefer to employ at the substations has a circuit which is normally closed, preferably through the agency of a spring desirably formed of iron either in whole or in part, the closed circuit containing a relay or operating electromagnet of the signal. A signal that is very suitable for the purpose is a single-stroke bell whose hammer is normally maintained against the gong to open an alternative path containing the bell-magnet that includes a back contact of the bell-magnet armature, as in ordinary make-and-break circuits. The aforesaid spring is caused to open the circuit normally closed thereby through the agency of an electromagnet constituting the signal-receiver proper, through which incoming

high-frequency signaling-currents pass, and a permanent magnet included in the same magnetic circuit with the core of the electromagnet and provided with a pole-piece opposed to the spring or iron portion thereof, which in cooperation with the core of the electromagnet alternately polarized by the incoming signaling-currents will effect a vibration of the spring that will maintain the same in open circuit. I believe it to be novel with me to thus maintain a relay or bell-operating electromagnet in a closed circuit containing a circuit-breaker (as the aforesaid spring) to cause the attraction of the armature of the said relay to maintain open another circuit, which would effect its operation.

I will explain my invention more fully by reference to the accompanying drawings, in which—

20 Figure 1 illustrates a composite telephone and telegraph circuit equipped in accordance with my invention. Fig. 2 is a view of a modified circuit arrangement of apparatus at a telephone-station of such a composite system.

25 Like parts are indicated by similar characters of reference in both views.

Referring first more particularly to Fig. 1, I have illustrated the transmission-line *a*, 30 that may be employed for connecting telephone-stations and telegraph-stations, there being indicated two telegraph-stations *b* at the extreme ends of the line and two telephone-stations *c* at intermediate points of the line. I do not wish to be limited, however, to such relative arrangement of stations. As the telegraph instruments illustrated will be readily understood by those skilled in the art, I do not deem a description 35 thereof to be essential. I have indicated impedance devices *d* to permit the passage of telegraphic current between the telegraph-stations and prevent the passage of voice-currents through the telegraph-stations. 40 Where each telephone-station is connected with a transmission-line, there is desirably included in the branch extending to the telephone-station apparatus a condenser *e* for the purpose of preventing the passage, or 45 rather reducing the passage, of telegraphic currents through the telephone apparatus. At each telephone-station there is contained well-known telephonic apparatus—namely, 50 a receiver *f*, a transmitter *g*, and an induction-coil containing a secondary *h* and a primary *i*. When the receiver at each station is off its hook, the branch *k*, extending to the transmission-line, is closed for the purpose of enabling conversation between the stations. 55 It has been found in practice that the condenser *e* is not sufficient to prevent the transmission of telegraphic currents through the telephonic apparatus. To prevent this current from affecting telephonic apparatus in 60 the system shown in Fig. 1, there is included

in shunt to the receiver and the secondary coil an agency serving to prevent the transmission of telegraphic currents through the receiver. This agency desirably is in the form of an impedance-coil *l*, which may, if desired, be adjustable by having its core rotatably mounted upon an arm, as indicated. This impedance-coil is preferably of quite low ohmic resistance, so as to afford an easy path for the comparatively straight currents emanating 75 from the telegraph-stations, but of high impedance to obstruct the high-frequency voice-currents.

Referring to Fig. 2, in order to prevent the telegraphic currents from passing through the primary coil, which would cause currents to be induced in the secondary coil, I provide an impedance device *l*. This primary coil *i* is shunted by the impedance device *l*, which has the same general nature as described in 80 connection with Fig. 1. At each station there is provided a signal-receiver, that is normally included in circuit with the transmission-line through the agency of the telephone switch-hook *m* at the corresponding 85 station, and a spring *n*, thrust by the switch-hook against its normal contact when the receiver is upon its switch-hook. The element that receives the incoming signaling-current is a relay or signal-receiver *o*, (shown grounded,) whose core is of soft iron and which acts also as a conductive connection in the local circuit *p*, as will be presently set forth. This core has at one end a contact, preferably platinum, against which a spring *q* bears by 90 its own tension. This spring *q* is made of iron, at least where it is opposed to the magnet, and constitutes a part of the circuit *p*. The electromagnet *o* is provided with a permanent magnet *r*, so that when incoming 95 high-frequency signaling-currents are passed through the magnet *o* the spring *q* is forced away from physical contact with the core of the magnet *o* to open the circuit *p*, with the results to be hereinafter set forth. The permanent magnet *r* is desirably provided with a soft-iron screw *s*, that determines the reluctance of the magnetic circuit afforded by the permanent magnet and the core of the electromagnet. The circuit *p* contains a 100 source of current, as a battery *t*, and also an electromagnet or relay *u*. In the present instance the relay *u* has its armature provided with a hammer that is adapted to strike against a gong *u'*, which hammer is 105 desirably normally held against the gong as the electromagnet *u* is normally energized. When an incoming signaling-current of sufficiently high frequency is passed through the electromagnet *o*, the circuit *p* is opened by 110 the removal of spring *q* from its contact, as stated, whereupon a second circuit containing the battery *t* is closed by way of the back contact of the armature in the manner of 115 direct-current make-and-break bells. The 120

transmitter of signaling-current is desirably of the form indicated, having a primary winding v , included in a local circuit with a battery v' and controlled by a key v^2 , which in addition to closing the primary local circuit also connects the secondary v^3 to said primary with the transmission-line. The primary constitutes also the energizing winding of an electromagnet whose armature v^4 when not attracted closes the primary circuit (assuming the key v^2 to be depressed) and while attracted serves to open the said circuit somewhat in the manner of the signal-causing device u . In this way a current of extremely high frequency may be impressed upon the line which is not capable of operatively affecting the telegraph instruments also connected with the line, the impedance-coils d acting to prevent the transmission of these high-frequency currents. When the telephone instruments are in use, the receivers are removed from their switch-hooks, whereby the signaling-receivers e are cut out of circuit and the transmitters g and the receivers are cut into circuit. It will be seen that a subscriber may signal whether his telephone is on or off its hook without unpleasant noises in his receiver, which result is accomplished by connections of the key v^2 , which serves to cut out the corresponding receiver when it is actuated. Each switch-hook is preferably of the construction illustrated, having a plunger w , adapted for insertion between the springs n and x to open the circuits containing the telephone instruments f and g and to close the circuits containing the signal-receiver. These springs n and x by their own resiliency close upon their alternate contacts when the receivers are removed from their switch-hooks to cut out the signal-receivers and include the telephone instruments in circuit. Some suitable form of lightning-arrester or current-protector y is desirably contained in each telephone branch.

The telegraphic currents that may pass through the telephone branches have their characteristics somewhat modified in their transmission, as by their condensers in the telephone branches, so that all such currents may not pass through the inductive shunts about the telephone apparatus. In such event such inductive shunts serve to smooth the current to prevent violent clicks in the telephone-receivers.

I have used the phrase herein "of low ohmic resistance," meaning that the ohmic resistance is low as compared with the portion of the telephone-conductor that is shunted by the same, so that the telegraphic currents will select this part of low resistance rather than pass through the telephonic instruments.

It is obvious that changes may readily be made from the system herein shown without

departing from the spirit of my invention, and I do not, therefore, wish to be limited to the precise system and details thereof illustrated. Having thus described my invention, I claim as new and desire to secure by Letters Patent—

1. In a composite telephone and telegraph system, the combination with a transmission-line, of telegraph-stations united thereby, telephone-stations which the said transmission-line serves to connect in connecting branches from the said transmission-line and means for shunting the telegraph-currents from the telephone instrument at the substations, the said means comprising an impedance device of low ohmic resistance in a shunt or by-path about the corresponding receiver and secondary coil, substantially as described. 75

2. In a composite telephone and telegraph system, the combination with a transmission-line, of telegraph-stations united thereby, telephone-stations which the said transmission-line serves to connect in connecting branches from the said transmission-line and means for shunting the telegraph-currents from the telephone instruments at the substations, said means being in the form of an impedance device of low ohmic resistance in shunt of one of the windings of the transmitter-induction coil, substantially as described. 85

3. In a composite telephone and telegraph system, the combination with a transmission-line, of telegraph-stations united thereby, telephone-stations which the said transmission-line serves to connect, connecting branches serving to unite said telephone-stations with said transmission-line, condensers 100 in said connecting branches between the telephone-stations and the transmission-line and instrumentalities connected with said branches between the telephone-stations and the condensers, said instrumentalities serving to shunt telegraph-currents leaking through the condensers and themselves not materially deflecting telephone-currents passing between telephone-stations and the transmission-line. 115

4. In a composite telephone and telegraph system, the combination with a transmission-line, of telegraph-stations united thereby, telephone-stations which the said transmission-line serves to connect, connecting 120 branches serving to unite said telephone-stations with said transmission-line and instrumentalities at the telephone-stations serving to shunt telegraph-currents leaking toward the telephone apparatus and themselves not 125 materially deflecting telephone-currents passing between telephone-stations and the transmission-line. 135

5. In a composite telephone and telegraph system, the combination with a transmis-

5 sion-line, of telegraph-stations united there-
by, telephone-stations which the said trans-
mission-line serves to connect, connecting
branches serving to unite said telephone-sta-
tions with said transmission-line, condensers
10 in said connecting branches between the tele-
phone - stations and the transmission - line
and instrumentalities connected with said
branches between the telephone-stations and
15 the condensers, said instrumentalities serv-
ing to shunt telegraph - currents leaking
through the condensers and themselves not
materially deflecting telephone-currents pass-
ing between telephone-stations and the trans-
mission-line and including a current carrying
winding of high impedance and low ohmic re-
sistance.

6. In a composite telephone and telegraph
system, the combination with a transmis-
20 sion-line, of telegraph-stations united there-

by, telephone-stations which the said trans-
mission-line serves to connect, connecting
branches serving to unite said telephone-sta-
tions with said transmission-line and instru-
mentalities at the telephone-stations serving 25
to shunt telegraph-currents leaking toward
the telephone apparatus and themselves not
materially deflecting telephone-currents pass-
ing between telephone - stations and the
transmission-line, said instrumentalities in-
cluding a current-carrying winding of high
30 impedance and low ohmic resistance.

In witness whereof I hereunto subscribe
my name this 10th day of January, A. D.
1903.

HARRY O. RUGH.
